H. W. ROUNTREE

WARDROBE TRUNK LOCK

Filed May 11, 1922

UNITED STATES PATENT OFFICE.

HENRY W. ROUNTREE, OF RICHMOND, VIRGINIA, ASSIGNOR TO H. W. ROUNTREE & BROTHER TRUNK & BAG CO., OF RICHMOND, VIRGINIA, A CORPORATION.

WARDROBE-TRUNK LOCK.

Application filed May 11, 1922. Serial No. 560,189.

To all whom it may concern:

Be it known that I, HENRY W. ROUNTREE, a citizen of the United States, residing at Richmond, in the county of Henrico and 5 State of Virginia, have invented certain new and useful Improvements in Wardrobe-Trunk Locks, of which the following is a specification.

My present invention has reference to improvements in that type of trunks whose wardrobe or clothes hanging compartment is provided with a closure or door that is hinged along one edge of the said compartment and whose other edge is provided with 10 key controlled locking elements adapted, when the hinged member or door is swung to its closed position, to interlock with latch engaging sockets in that edge of the body of the wardrobe section that is hingedly connected to the bureau of the trunk.

As is well known to trunk manufacturers of wardrobe trunks provided with a hinged door for closing the wardrobe compartment of the trunk, such hinged doors are not used 25 in the manufacture of the modern type of wardrobe trunks having a hinged top end, and in place of the said lock controlled hinged door, curtains or follower boards are usually substituted.

My invention primarily has for its object 30 to provide for dispensing with the use of the more or less expensive follower devices, included in the modern type of wardrobe trunks for holding the hung garments in the 35 wardrobe section of the trunk, and for the restoration of the hinged door with the key-controlled means that secure the locking elements against unauthorized operation and, at the same time, provide for locking the 40 hinged end top when the wardrobe compartment door is closed, to thereby retain the wardrobe section of the trunk at its closed or locked position against those who might have access to the bureau section of the trunk 45 when the trunk is open, and thus prevent the hinged top end of the wardrobe section from being lifted so long as the hinged door or wardrobe section closure member remains at the locked condition.

With other minor objects in view that will be hereinafter apparent, my invention consists in the peculiar features of construction and combination of parts fully stated in the following description, specifically pointed

out in the appended claims and illustrated in 55 the accompanying drawing, in which:

Figure 1 is a perspective view of the modern type of wardrobe trunk provided with a lock equipped hinged closure member or door, the latter and the hinged top of the 60 wardrobe section of the trunk being provided with my improvements.

Figure 2 is a detail cross section of the top 65 ends of the two opposing trunk sections with my improvements applied.

Figures 3 and 4 are perspective views of the auxiliary interlocking elements that secure the wardrobe section door and the hinged top end together.

In the drawings, is illustrated a modern 70 type of wardrobe trunk whose bureau section 1 and wardrobe section 2 are hinged together in the usual way, and in the said illustration the wardrobe section is provided with the bowed form of hinged top section 3 which, 75 as shown, has the usual inside filler 30 whose under face is flat so that, when the top end is closed down, the said under face of the filler 30 fits snugly over the usual trolley devices 4 upon which the clothes hangers 5 80 are suspended in the usual manner.

6 designates the closure member or door which is hinged along one edge 60 to the outer vertical edge 20 of the wardrobe section.

In practice, the door 6 of the wardrobe trunks may be provided with compressor devices on the inner side (not shown) for holding the suspended garments in closed up 90 relation, and as shown the said door is provided with key controlled locking latches 7-7 along the outer or free edge, which latches engage suitable lock receiving sockets 8-8 on the outer edge of the inner vertical wall 21 of the trunk section 2.

In practice, the several latches 7 are simultaneously moved into and out of their locking adjustments by key controlled devices which may be of any well known type, for example, as shown in Patent #928,904. 100

In my construction of wardrobe trunk of the kind stated, the door 6 is provided with a supplemental latch 9 which in the simplest form is shaped as shown in detail in Figure 4, and the said latch 9 is riveted or otherwise secured along the inner face of the upper edge of the door 6 with its angled or hook end 90 positioned for closing into a

latch receiver 10 secured upon the under flat side of the filler 30 of the hinged top end 3 and along the front edge thereof, as is clearly shown in Figure 1, the said receiver 5 10 in the simplest form, being shaped as shown in detail in Figure 3, the loop or latch receiving portion being sufficiently wide to provide for the ready entry therein, of the latch hook 90, when the door is closed and 10 locked over the wardrobe section as is best indicated in Figure 2. The locking element 10, when the trunk members are closed together, projects down over the front rail or cross bar 11 of the trolley devices and 15 thereby permits the bottom of the hinged top to close down against the rail 11 to the usual position for preventing the clothes hangers jarring off the trolleys as the trunk is being transported and moved about, when 20 handling it in its closed condition.

My improved means for locking the wardrobe section of a trunk of the kind stated and shown, is so simple that the modern types of wardrobe trunks may be readily 25 equipped with the door types of closures for the wardrobe section, since the said improvements provide for readily using such door type closures with trunks having the hinged top ends as the said improvements serve to hold the said hinged top ends locked to their 30 closed position so long as the hinged door 6 is locked to its closed position.

It is obvious that with my auxiliary locking means applied to the hinged door 6, and 35 the hinged top 3, as stated and shown, while access may be readily had by anyone to the bureau section of the trunk when the said trunk is open, the wardrobe section remains closed against access by unauthorized persons or, in other words, access to 40 the said wardrobe section can be had only by those having the proper key for unlocking the door 6 which latter, when unlocked and swung out, as shown in Figure 1, releases the top 3 and thus provides for free access to the 45 wardrobe section, it being also understood that when closing the said wardrobe section,

the top 3 is first closed down and as the door is swung to its closed position and locked as described, the top 3 is likewise locked down 50 by reason of the members 9 and 10 interengaging, as before mentioned.

While I have shown but one auxiliary locking means 9 and 10, a plurality of such devices may be used along the upper edge 55 of the door 6 and also along the lower edge of the door and the bottom end of the wardrobe section, as described.

From the foregoing taken in connection with the drawing, the advantages of my 60 improvements will be readily apparent to manufacturers of wardrobe trunks and to those familiar with the use thereof.

What I claim is:

1. The combination in a wardrobe trunk 65 composed of two sections hinged together, one of said sections having a hinged top; a door hinged to said section which has the hinged top, means for locking said door in closed position with respect to its section and 70 cooperative connections between said door and said hinged top for holding said hinged top down when said door is in the closed position.

2. In a trunk of the character described 75 whose wardrobe section includes garment supporting trolley elements at the upper end, and a hinged top at such end whose bottom closes down onto the said trolley elements, and a hinged door that constitutes 80 the closure for the clothes compartment of the said trunk section; and key controlled locking devices for locking the hinged door of the wardrobe section; auxiliary locking devices on the door and the hinged top of 85 the wardrobe section that lock the top when down as the door is at its closed position, the said auxiliary devices including a hook projected inwardly from the inner top edge of the door, and a keeper secured to the underside of the hinged top and projected down in advance of the trolley elements to receive the hook on the door when it is closed. 90

HENRY W. ROUNTREE.
